CLOTHES DISPLAY RACK

Barry Axelrod, Los Angeles, Calif., assignor to Laurel
Line Products, Los Angeles, Calif.

Filed Feb. 18, 1971, Ser. No. 116,742

Term of patent 14 years

Int. Cl. D6—06

U.S. Cl. D80—8

FIG. 1.

FIG. 3.

FIG. 4.

FIG. 2.

FIG. 1 is a perspective view of a clothes display rack showing my new design;

FIG. 2 is a side view of FIG. 1;

FIG. 3 is a top view of FIG. 1; and

FIG. 4 is another side view, showing the rack in an extended position.

I claim:

The ornamental design for a clothes display rack, as shown.
